(57) **CLAIM**

We claim the ornamental design for a container finish, as shown and described.

DESCRIPTION

FIG. 1 is a perspective view of a container in accordance with our new design;

FIG. 2 is a front elevation view thereof;

FIG. 3 is a top plan view thereof;

FIG. 4 is a left side elevation view thereof, the right side elevation view being a mirror image; and,

FIG. 5 is a rear elevation view thereof.

Dash-dash-dash broken lines shown in the drawings represent environmental structure and are not part of the claimed design.

Dash-dot-dash broken lines shown in the drawings represent boundaries of the claimed design and are not part of the claimed design.

1 Claim, 4 Drawing Sheets
